ATTORNEY

UNITED STATES PATENT OFFICE.

FRANK D. GOULD, OF OAKLAND, CALIFORNIA.

DESIGN FOR AN AUTOMOBILE-TOP.

• 57,041.

Specification for Design.

Patented Feb. 1, 1921.

Application filed December 24, 1919. Serial No. 347,231. Term of patent 14 years.

To all whom it may concern:

Be it known that I, FRANK D. GOULD, a citizen of the United States, residing in the city of Oakland, county of Alameda, and State of California, have invented a new, original, and ornamental Design for an Automobile-Top, of which the following is a specification, reference being had to the accompanying drawings, forming part thereof.

Figure 1 shows a side elevation of an automobile top embodying my invention.

Fig. 2 shows a rear elevation of the same.

I claim:

The ornamental design for an automobile top, as shown.

FRANK D. GOULD.

Witnesses:

W. W. HEALEY,
JOHN H. HERRING.
